UNITED STATES PATENT OFFICE

149,588

DESIGN FOR AN ASH TRAY OR THE LIKE

Louis H. Rezos, Arlington, Va.

Application June 28, 1946, Serial No. 131,142

Term of patent 3½ years

(Cl. D85—2)

To all whom it may concern:

Be it known that I, Louis H. Rezos, a citizen of the United States of America, residing at Arlington, in the county of Arlington and State of Virginia, have invented a new, original, and ornamental Design for Ash Trays or the like, of which the following is a specification, reference being had to the accompanying drawing, forming part thereof.

Fig. 1 is a side view of an ash tray showing my new design, and

Fig. 2 is a top plan view thereof.

I claim:

The ornamental design for an ash tray or the like, as shown.

LOUIS H. REZOS.
